UNITED STATES PATENT OFFICE

JAMES T. KETCHUM, OF CHICAGO, ILLINOIS

SECTIONAL HEATING BOILER

Application filed December 3, 1927. Serial No. 237,443.

My invention broadly relates to improvements in heating systems for dwellings, buildings, and edifices in general; and more particularly to improvements in sectional heating boilers adapted for gas or oil consumption.

The object of my invention is to provide a device of the kind described that will be economical in fuel, efficient in operation, and particularly adapted for expansion in units to meet the need for a given steam or vapor output.

Another object of my invention is to provide a sectional boiler construction with novel means for the utilization of incandescent gases therein and draft regulation therefor.

Other objects and advantages of the method and construction herein employed will appear more fully in the following specification when taken in connection with the accompanying drawings, in which,

Figure 1 is a sectional view, partly in elevation of a boiler embodying my invention, parts being broken away to show more clearly the water level therein.

Figure 2 is a detail view partly in section with a portion of the front casing of one of the boiler sections broken away.

Figure 3 is an elevational view partly in section, illustrating the damper regulation.

Figure 4 is a side elevation of my device.

Figure 5 is a front elevation thereof.

With more particular reference to the drawings wherein similar characters of reference indicate corresponding parts in the several views, A designates one of my sectional boiler units comprising the top wall 11 and side walls 12 equipped with the usual refractory lining 13, the inclosure thus formed providing the usual fire box or combustion chamber 14 having a space for the reception of the boiler 15, which includes the tubes 16 communicating with the front head 17 and the rear head 18, both of which open into steam dome 19. The steam dome has a part 19' which projects into the front head section 17 in this manner, serving as a baffle for steam to the outlet port 52. In the fire box or combustion chamber 14 of the

boiler A' is a baffle plate 20 which serves to divide the rearward portion of the combustion chamber 14 and the lower portion of the space occupied by the tubular boiler 15, into two separate divisions 15' and 15'', respectively. By means of the baffle plate 20, the products of combustion impinging thereagainst, are compelled to travel upwardly and over the top portion thereof and then to descend through the division 15'', thence passing to the smoke stack hereinafter described more fully. The rearward end of the chamber 15'' has a flue outlet 21 which enters into a smoke stack hood 22,--the hood being equipped with a hand hole opening 23 for the removal of various deposits that may have accumulated within and around the combustion chamber. The smoke stack hood 22 is also connected to a stack 25 which has a damper regulator 26 provided with inlet and outlet openings 27, 28,--the opening 27 communicating with the smoke stack hood, while the opening 28 communicates with the upper stack 25.

The damper regulator 26 is provided with a draft valve 29 having one wing 30 extending within the interior of the regulator 26, and another wing 31 located on the outside of the regulator, the outside wing serving to close the valve opening 32 which communicates directly with the atmosphere. The opening 28, it will be observed, is partially closed by the inner wing 30 which extends within the interior of the regulator 26, the down draft in this manner being eliminated.

The regulator valve 29 as best shown in Figure 3, is provided with pockets 33 which latter accommodate annular glass pivots 34 which are adjustable by the set screws 35, which are mounted in bearings 36 on regulator 26. By this arrangement it will be understood that regulator valve 29 is readily operated and swung to a greater or less extent by down drafts of air impinging thereagainst.

The upper part 25' of the smoke stack 25 has secured thereto a T joint which is connected to a pipe 38 having direct communication with the chamber occupied by the boiler A, the pipe 38 having incorporated

therein a conventional damper 39. When the boiler is initially fired, the products of combustion are preferably passed through the pipe 38 by the damper 39 until sufficient heat is discharged therein to dissipate whatever natural moisture and condensation may have accumulated in the boiler,—after which the damper 39 is closed and the boiler operated normally by causing the incandescent gases to pass upwardly and downwardly past the baffle plate 20 to the smoke stack hood 22, and thence through the damper regulator 26 and the upper part 25' of the stack.

The rearward part 15" of the boiler A of the chamber 14 is provided with an inspection and soot removing box 40,—the boiler itself being normally held in position by angle iron brackets 41.

The boiler A is made up of a plurality of individual sections to form a complete unit which is capable of being increased or decreased by adding to or taking away one or more sections. The front head 17 and the rear head 18 have recesses 42 to accommodate tie rods and nuts 43 whereby the sections of the boiler may be joined together to provide units adaptable to different load conditions. The rear head 18 is provided with a supply pipe 44 having a suitable valve 45 connected to a head of water whereby the boiler may be filled. The front head 17 has a water gauge 46 connected to a pipe 47 entering the lower portion of the head 17. The water gauge comprises the usual glass tube 48 and the valves connected thereto, whereby the water level of the boiler may be ascertained at all times.

The upper end of the pipe 47 is equipped with an elbow connected with a transversely extending pipe 49 and also with a steam gauge 50. It will be noted that the steam dome 19 protrudes into the head 17, its lower portion being cut away while an upper portion 51 is extended into the header 17 to act as a baffle plate for steam generated therein.

In the top wall of the chamber 17 a port 52 is provided, which enters into a steam hood 53, the latter having an exit port 54 communicating with the steam heating system employed. The safety valve 55 and hand hole ports 56 also enter into the chamber 15.

The combustion chamber is provided with a fuel burner 57 having the usual combustion manifold 58. The supply pipe and manifold 59 has a plurality of valves 60 which serve to regulate the fuel feed. Each of the burners 67, it will be seen, is provided with a pilot light 61 and a valve 62, which has connection with the manifold 59. With a view to inspecting the combustion chamber 14, a plurality of sight windows 63 having pivotally mounted lids 64, are provided.

The function and mode of operation of my device has been in great measure indicated from the foregoing detailed description, and

will be more fully apparent by the following explanation upon referring to the several views of the drawings.

Upon igniting the gaseous fuel from the burner 57 by the pilot light 61, the incandescent gases, assuming the boiler to be cold, are first permitted to pass upward through the chamber 15' to the pipe 38, and thence into stack 37. In a short space of time, the usual initial condensation and moisture in the combustion chamber is dissipated, after which the damper 39 is closed and the products of combustion led over and around the baffle plate 20 to the smoke stack hood 22, and thence through the valve regulator to the upper stack to find their way into the atmosphere. This is the normal operation of the boiler. Conditions may arise when a draft down the stack will impinge against the wing 30 of the valve regulator 29 which will turn about the pivots 34 in a manner to partially close the passage-way of the stack, and at the same time to permit the outside atmosphere to enter through the port of the valve 32. The extent to which the valve regulator will swing will depend upon the pressure of the down draft and the equalizing pressure of the atmosphere of the room in which the boiler is located, which will enter when the outside wing 31 is raised. This feature of my invention, it will be noticed, provides an automatic regulation of the draft which will require no manual attention. The portable boiler described is particularly adapted to be set up in a short space of time, and should at any time the heating load requirements demand a further increase of steam production, sections can be added on by merely passing the tie rods 43 through the additional section, and making connections thereto by the nuts threading thereon.

While I have described and illustrated with particularity a preferred embodiment of my invention, it will be readily understood by those skilled in the art to which my invention appertains that my device is susceptible of considerable modification and variation; hence I do not confine myself to the specific details as set forth, but wish to avail myself of such changes and modifications as fairly fall within the scope of the appended claims.

What I claim as new and desire to secure by Letters Patent is:

1. A boiler comprising a plurality of portable tubular sections joined to form a single expansible boiler, a common combustion chamber and an individual fuel burner for each of said tubular sections, a pair of head sections joining the ends of each of the tubular sections, a steam dome connecting and communicating with both of said head sections, said steam dome having an integral portion projecting partly into one of the head sections thereby compelling the passage of

steam to one side thereof, said integral portion being formed by the cutting off of a front lower portion of said steam dome and serving as a baffle for steam in said dome.

- 5 2. A boiler comprising in combination a plurality of individual portable tubular sectional units detachably joined by elements insertable in the units and clampingly connected thereto, each of said sectional units
10 communicating with a front head and a rear head, said front head and said rear head being operatively connected to a steam dome, said steam dome having a steam baffle plate formed by the cutting away of the under-
15 neath section of the dome, a second baffle plate arranged in a combustion chamber forming a part of said boiler, said second baffle plate providing a means for directing products of combustion upwardly and downwardly
20 through said tubular boiler units, substantially as described.

In testimony whereof I have signed my name to this specification.

JAMES T. KETCHUM.
